UNITED STATES PATENT OFFICE.

DANIEL L. BRAINE, OF NEW YORK, N. Y., ASSIGNOR, BY MESNE ASSIGNMENTS, TO COMPOSITE TIE-PLATE CORPORATION, OF NEW YORK, N. Y., A CORPORATION OF NEW YORK.

RAIL SUPPORTING AND FASTENING DEVICE.

1,081,575.

Specification of Letters Patent.

Patented Dec. 16, 1913.

Application filed March 15, 1913. Serial No. 754,502.

To all whom it may concern:

Be it known that I, DANIEL L. BRAINE, a citizen of the United States, residing at New York city, in the county of New York and State of New York, have invented 5 certain new and useful Improvements in Rail Supporting and Fastening Devices, of which the following is a specification.

This invention relates to improvements in 10 rail supporting and fastening devices, and has for its object to provide such a device by means of which a rail may be readily secured in place, or removed therefrom, without necessitating the complete removal 15 of the securing spikes, as is necessary in the present-day practice.

Another object is to provide an improved 20 form of tie-plate, which may be readily and cheaply stamped, or similarly formed, from metal.

Still another object is to provide an improved screw spike, adapted to co-act with such frame, to maintain a rail in position as the same wears down upon its supporting 25 block, capable of adjustment and following the base of said rail downwardly, and continuing to maintain the same in position.

Still another object is to provide a spike 30 which, in addition to performing the above functions will co-act with a tie-plate, so as to provide a supporting or reinforcing means for the head of the spike, to prevent bending or outward turning of the latter.

Other objects will be made apparent and 35 set forth in the following specification and accompanying drawings, in which—

Figure 1 is a side elevation of my combined device, showing the rail in section; Fig. 2 is a plan view of the construction 40 shown in Fig. 1, one of the spikes being removed, and one of the spikes being in position to permit the removal of the rail; Fig. 3 is an end elevation of my device; Fig. 4 is a detail section showing the spike 45 in original holding position; Fig. 5 is a similar view, showing a spike rotated to follow the rail down, after the latter has worn down the supporting block; Fig. 6 is a perspective view of the tie-plate, or metal frame, as I term it; Fig. 7 is a perspective 50 view of the supporting block; Fig. 8 is an inverted plan view of the head of the spike; and Fig. 9 is a perspective of the same.

Like numerals and characters refer to like

elements throughout the drawings, in 55 which—

10 designates the usual form of rail, having a flange or base, 11. A supporting block 12 is adapted to be placed beneath the base 11 of the rail, 10, and serves as a support 60 for the same, being itself located upon the usual tie or sleeper, 13. A metal tie-plate or frame, 14, comprising the top portions 14^a, spaced apart a distance substantially equal to the width of the rail-base, 11, and 65 the sides 14^b, is adapted to rest on the supporting block 12, the sides 14^b closely fitting the sides of the block and terminating short of the upper surface of the tie, 13. The sides, 14^b, are preferably cut away between 70 the top portions 14^a and 14^b, as indicated by numeral 14'. As shown in Fig. 1, this will prevent the weight of the rail or passing train being transmitted to any part of the metal frame, 14, the supporting block, 12, 75 receiving the entire direct weight, and consequent crushing force.

Provided in each of the top portions, 14^a, are the spiking apertures 14^c. These apertures may be stamped or punched from the 80 metal, and are shown as opening into the space between the respective top portions. The peripheries 14^d of the apertures are offset as shown in Fig. 6, thereby forming in each periphery a shoulder designated by the 8 numerals 14^e, respectively. This shoulder is located, in each instance, at approximately the mid-point of the periphery surrounding the corresponding spiking apertures, as is clearly shown in the drawings, for a purpose hereinafter described. 90

The supporting block, 12, will be provided with drilled-out spiking holes, 12^a, located to align with the corresponding opening of the spiking apertures in the metal frame, 14. Co- 95 acting with the block and frame is the screw-spike, 20, having the threaded stem, 20^a, (see Figs. 4 and 5), and the circular head, 20^b, from which projects outwardly the upper non-circular head, 20^c, adapted to be engaged by a wrench, or etc., for rotation of 100 the spike. This head, 20^b, is provided with the helical under surface, 20^d, of inclination reverse to that of the screw thread of the stem, 20^a, i. e., where the thread of the stem 105 is right-handed, as shown in this instance, the helix of the under side 20^d of the screw-head 20^b is left-handed. The head 20^b is

further provided with the cutaway portion 20^e, preferably cut away in a plane parallel to the axis of the stem, 20^a. What I term a supporting shoulder, 20^f, is formed on the under side of the head 20^b, and extends partially around the stem 20^a of the spike 20, as is shown clearly in Figs. 8 and 9. This shoulder 20^f is also provided with the helically inclined under side, the helix thereof being of a pitch approximately equal to that of the screw thread. This supporting shoulder, 20^f, terminates at one end, at 20^g, and at its other extremity originates flush with the under surface, 20^d of the head 20; said under surface being cut away as indicated by numeral 20^h in Fig. 8. The extremity 20^g of the shoulder, 20^f, in the construction shown, is located a slight distance forwardly of the cut-away portion 20^e of the head 20, relative to the direction of rotation of the screw spike.

The device when assembled is utilized as follows: The position of the rail with respect to gage, etc., is determined, and the supporting block 12 is placed beneath the base of the rail, upon the tie, 13. The metal frame, 14, is also fitted in place, the base, 11, of the rail, being located between the top portions 14^a, as shown in Figs. 1 and 2. The screw spike, 20, is then screwed down through the spiking apertures into the tie 13, in the position indicated by spike A, Fig. 2, with the cut-away portion 20^e parallel with the base of the rail. When all the spikes are in this position, the rail may be readily placed or removed, as will be obvious. The spike is then rotated, clockwise, in this instance, until the head thereof approximates the position of the spike shown in Fig. 4, at which point a portion of the head 20^b will project over and press down upon the base 11 of the rail, 10. As the rail wears down upon the supporting block 12, as indicated in Fig. 5, the spike 20 may be screwed in accordingly, the head, 20^b, following the base, 11, of the rail, 10, downwardly.

When in initial holding position, as indicated in Fig. 4, the extremity, 20^g, of the supporting shoulder 20^f will be adjacent the offset edge or shoulder, 14^e as the case may be, and as the spike is screwed downwardly, the supporting shoulder 20^f will ride over the said edge, being in constant contact therewith, owing to the similarity in pitch of the thread of the spike and the supporting shoulder, 20^f. Contact of this shoulder 20^f with the edge of 14^e serves to form a support for the head, so that outward bending or turning of the head of the spike, due to lifting or turning of the rail, will be prevented.

It will be apparent that the spike is so constructed that the same may be rotated approximately three-quarters of a revolu-

tion from what I term the initial holding position, as shown in Fig. 4, before the final holding position or adjusted position is reached, at which point it is advisable to change the supporting block, owing to the amount of wear thereon.

Reverse inclination of the helical under side 20^d of head 20 will enable the head of the spike to ride up over the rail-base 11, the latter being generally of greater thickness than the metal frame, 14. Furthermore, this reverse inclination enables a greater amount of "take-up" of the rail wear, for a slight rotation of the screw spike, since not only the downward movement of the head, owing to the rotation of the screw-thread, will actuate to draw the head down against the rail-base 11, but also this reverse inclination will cause an additive downward thrust by the screw spike head on the base of the rail. The supporting shoulder, 20^f, is constructed to clear the outer edge of the rail base, 11, as will be apparent.

When it is desired to remove the rail, or replace the same, it is merely necessary to rotate the spike to a position corresponding to that of spike A, Fig. 2, when the rail may be removed bodily without necessitating the removal of the supporting block or metal frame from the tie.

It will be apparent that I have provided a form of device which will enable ready adjustment as the rail wears down upon its supporting block, and in which a point of support or reinforcement against outward turning of the screw-spike head is always maintained.

While I have shown and described my device with more or less particularity, I do not wish to be unduly restricted to such showing or description, beyond the scope of the appended claims.

What I claim is:

1. In combination, a rail supporting means, a frame having a top portion adapted to rest on said means and said top portion being provided with an aperture and a reinforcing means, a screw spike adapted to be inserted through said aperture and screwed down to secure a rail base in position, said spike being provided with means to coact with said reinforcing means when in secured position to reinforce said spike against bending, said means being constructed to permit further screwing down of said spike as said rail base is lowered.

2. In combination, a supporting block, a supporting member, a reinforcing member carried on said supporting member, a shoulder carried by said member, a screw spike having a head adapted to secure a rail base on said supporting block, said head having means coacting with said shoulder to reinforce said head when in secured position.

with respect to said rail base, said means and said shoulder being constructed to permit further screwing down of said spike when said rail base is lowered, at the same time maintaining said reinforcement.

3. In combination, a supporting block, a frame having a top portion adapted to rest on said block, a spiking aperture in said top portion, a portion of the periphery of said aperture being offset with respect to the remainder thereof to form a shoulder, a spike adapted to be inserted through said aperture, said spike being provided with a screw-threaded stem and a circular head, said spike being provided with a helically inclined supporting shoulder, located on the under side of said head, the pitch of said shoulder being approximately equal to the pitch of the thread of said stem, said shoulder of said spike being adapted to co-act with the shoulder of said top portion to support said head of said spike when in holding position, the under surface of said head being helically inclined in a direction reverse to that of said supporting shoulder and thread.

4. In combination, a supporting block, a frame having a top portion adapted to rest on said block, a spiking aperture in said top portion, a portion of the periphery of said aperture being offset with respect to the re-

mainder thereof to form a shoulder, a spike adapted to be inserted through said aperture, said spike being provided with a screw-threaded stem and a circular head, said spike being provided with a helically inclined supporting shoulder, located on the under side of said head, the pitch of said shoulder being approximately equal to the pitch of the thread of said stem, said shoulder of said spike being adapted to co-act with the shoulder of said top portion to support said head of said spike when in holding position, the under surface of said head being helically inclined in a direction reverse to that of said supporting shoulder and thread.

In testimony whereof, I have subscribed my name.

DANIEL L. BRAINE.
